PLYWOOD KNOCKDOWN BOX

George H. Osgood, Tacoma, Wash.

Application May 1, 1934, Serial No. 723,337

1 Claim. (Cl. 217—12)

This invention relates to plywood boxes and more especially to such boxes as may be shipped in knock-down condition from the box factory to the user and may be assembled by him for use.

5 The objects of my invention are, first, to provide a strong and quickly assembled box; which, second, may be quickly knocked down after it has been assembled; third, in which the cover is removably fastened in place; fourth, in which no 10 glue or nails are used to secure the several parts together; fifth, in which the several sides are interlocked; and sixth, in which unskilled labor may be used in the making and assembling of the box.

I attain these and other objects by the devices 15 and arrangements illustrated in the accompanying drawing, in which—

Fig. 1 is a perspective view of my improved box assembled and ready for use, a portion of the cover being broken away to reveal the construction; Fig. 2 is an enlarged elevation of one of the upper corners of the box; Fig. 3 is a plan thereof; Fig. 4 is a plan of the spring steel clip used for securing the two sides forming a corner together; Fig. 5 is a vertical section of the upper edge of 25 the box showing the means for fastening the cover in place thereon; Fig. 6 is a plan of the spring steel snap used for securing the cover to the sides of the box; Fig. 7 is a plan of the box as shipped in knock-down condition from the box 30 factory; Fig. 8 is a section of the joint between the bottom and one of the sides, when in knock-down condition, and showing one of the staples whereby the sides are secured to the bottom; and Fig. 9 is a similar view thereof, when the said 35 side is assembled in normal position.

Similar numerals of reference refer to similar parts throughout the several views.

This box is a variation of that shown in my application for patent for improved knock-down 40 wooden box, filed under Serial No. 713,112, wherein in all the six sides of the box were secured together by glued tape.

Referring to the drawing, it will be seen that the box comprises a bottom board 1, two end boards 2 and 3, two side boards 4 and 5, and a cover 6. All these sides are made of three-ply veneer wood.

Each edge of the bottom 1 is provided with tenons 7 formed integral therewith. These tenons are rectangular in form and of substantial breadth, and extend out from the inner line of the bottom 1 distances equal to the thickness of the side into which each said tenon fits, as hereinafter described. The cover 6 is also of the same 55 size and form as the bottom 1 and is also pro-

vided with similar tenons 7 extending therefrom. In practice the bottom 1 and the cover 6 are similar in every respect.

Each end 2 and 3 of the box is provided with rectangular cuts or mortises 8 on its upper and lower horizontal edges, said mortises corresponding in number, position and breadth with their complementary tenons 7 extending from the bottom 1 and cover 6, and each is of a depth equal to the thickness of the bottom or cover which fits into it. The vertical edges of the sides 2 and 3 are provided with integral rectangular tenons 9, of substantial breadth, extending out from the inner line of the box a distance equal to the thickness of the sides 4 and 5.

The two sides 4 and 5 are each provided with rectangular cuts or mortises 8 on their upper and lower edges, said mortises corresponding in number, position, and width with their complementary tenons 7 on the bottom 1 and cover 6, and each is of a depth equal to the thickness of the bottom 1 or cover 6 which fits into it. The vertical edges of the two sides 4 and 5 are provided with mortises 10 corresponding in number, position and breadth with the complementary tenons 9 on the ends 2 and 3, and each is of a depth equal to the thickness of the said ends 2 and 3.

Thus it will be seen that each side is locked against sliding movement relatively to its contiguous sides by means of the mutual interlocking of the several tenons in their complementary mortises along each of its four sides, and that the edges of the box, though formed of tenon edges from alternate sides of the box, form substantially straight lines because each tenon extends, from the inner line of the box, a distance equal to the thickness of the adjacent side into which it fits.

Metal staples 11 secure the ends 2 and 3 and the sides 4 and 5 to the bottom 1, each said staple bridging an open space 12 (Figs. 7 and 8) between the contiguous edges of the bottom 1 and the said side, such space 12 being equal in width to the depth of the mortise which the staple 11 spans. These staples 11 are clinched on the inner side of the bottom and of the sides. When the box is to be folded or assembled for use the staples 11 are bent at "X" (Fig. 8) as the side 2 is turned on the corner line of the box so that its mortises 8 are entered by the tenons 7 of the bottom and so that its tenons enter the mortises in the said bottom. Thus the lower edges of all the sides 2, 3, 4 and 5 are secured permanently to the bottom 1 by metal means which is bendable or flexible in a lim-

ited sense, and which strongly attaches the said sides to the bottom against all bursting stress.

Each side 2, 3, 4 and 5 is provided with a vertical slit 13, extending downward from its upper edge 5 and positioned adjacent to each of its upper corners, all said slits being preferably equidistant from the outer corners of the box. The said four sides are attached together, against bursting stress by means of spring steel clips 14, each such 10 clip being formed substantially as shown in Figs. 2, 3 and 4, and having a central right-angle bend at 15 and two inward rectangular hooked ends at 16, said hooked ends being adapted to slide down into the slits 13 and to grip the respective sides; 15 the length of the arms of the clips 14 is such as to fit tightly around the corners of the box and into the slits 13, thereby preventing outward movement of either side of the box relatively to the other.

20 The cover 6 is secured to the box, against bursting stress, by means of snaps 17 (Figs. 5 and 6), which are shaped similar to the clips 14 except that the lower end alone of said snaps is provided with a complete hook 18 similar to the hooks 16, 25 while the end in contact with the cover 6 is provided with a simple right-angle bend 19. The cover 6 is provided with narrow slots 20 adapted to receive the ends 19 of the snaps 17 and the sides 2, 3, 4 and 5 are provided with coordinated slots 30 or holes 21. These holes 21 are wider than the slots 20, being adapted to receive the entire hook 18 of the snap 17, whereby the said snaps are inserted in place. These snaps 17 are also made of 35 spring steel and are operated by first inserting the hook 18 in the hole 21 and then raising the snap so

that the hook engages the top side of the hole, and then springing the bend 19 into the slot 20 in the cover, thereby holding the cover down on the box.

The cover, therefore, may be removed by simply 5 prying the ends 19 of the snaps 17 out of the slots 20 in the cover and allowing the said snaps to be swung out of the way. Thus the box may be opened and closed as often as required. When 10 it is desired to knock the box down, the cover is removed, then the four clips 14 are slid out of the slits 13, thus freeing the sides 2, 3, 4 and 5 from each other; they then may be pressed down flat, thus bending the staples 11.

Having, therefore, described my invention, 15 what I claim is:—

A plywood box comprising six sides, the corresponding edges of each side being complementarily tenoned and mortised together to prevent relative sliding movement; the bottom and four sides 20 being permanently secured together along their contiguous edges in spaced relation to each other by staples spanning the spaces between said parts; each said four sides being provided with two slits 25 extending downward from its top edge and positioned adjacent its upper corners; four spring steel clips, each clip being bent at right-angles at its center and provided with resilient hooked ends, each said clip being adapted to extend around the corner of the box, when assembled 30 and to have its hooked ends slid down the said slits and adapted to grip the inner and outer sides thereof; and means for removably fastening the cover to said four sides.

GEORGE H. OSGOOD.
